UNITED STATES PATENT OFFICE

171,067

PLATFORM SCALE

Franz Wagner, Chicago, Ill., assignor to Borg-Erickson Corp., Chicago, Ill., a corporation of Illinois

Application April 10, 1953, Serial No. 24,449

Term of patent 14 years

(CL. D52—10)

To all whom it may concern:

Be it known that I, Franz Wagner, a citizen of the United States, residing at Chicago, in the county of Cook and State of Illinois, have invented a new, original, and ornamental Design for a Platform Scale, of which the following is a specification, reference being had to the accompanying drawing, forming part hereof, and wherein

Figure 1 is a plan view in perspective of a platform scale embodying my new design;

Figure 2 is a side view; and

Figure 3 is a rear elevational view,

I claim:

The ornamental design for a platform scale, as shown.

FRANZ WAGNER.
